J. C. ANDREWS

SCREEN FOR EAVES TROUGHS AND THE LIKE

Filed Dec. 24, 1924

INVENTOR.
JAMES C. ANDREWS.
By *Edward Reed*

ATTORNEY.

Patented Aug. 24, 1926.

UNITED STATES PATENT OFFICE.

JAMES C. ANDREWS, OF DAYTON, OHIO.

SCREEN FOR EAVES TROUGHS AND THE LIKE.

Application filed December 24, 1924. Serial No. 757,892.

This invention relates to screens for eaves troughs and the like. It has been proposed heretofore to use screens of various kinds to prevent leaves and other foreign matter from entering eaves troughs but these screens have not, as a rule, been satisfactory, either because they were expensive to build or difficult to install, or because they were of such a character that they would become clogged with leaves or other matter.

One object of the invention is to provide a screen for an eaves trough which will be very simple in its construction, easy to install and which can be produced and installed at a low cost.

A further object of the invention is to provide such a screen which will be of such a character and so arranged that it will not become clogged by an accumulation of leaves or other matter thereon.

Other objects of the invention will appear as the device is described in detail.

In the accompanying drawings Fig. 1 is a perspective view of a portion of an eaves trough showing my screen applied thereto; Fig. 2 is an end elevation of the screen itself; Fig. 3 is a longitudinal sectional view of portions of two sections of the screen showing the means for connecting the same.

In these drawings I have illustrated one embodiment of my invention and have shown the same as applied to an eaves trough of standard construction. It will be understood, however, that the invention may take various forms and may be applied to eaves troughs of various kinds.

As here shown the eaves trough, 1, is substantially U-shaped in cross section and has the upper portion of its outer wall offset, as shown at 2, and provided at its upper edge with an inturned flange 3. The trough is secured to the supporting structure 4 by suitable fastening devices, which, as here shown, comprise nails 5 which extend through the outer and inner walls of the trough and into the supporting structure and which have mounted thereon spacing devices, such as tubes 6, which maintain the inner and outer walls of the trough in proper spaced relation one to the other.

The screen may be formed of foraminous material of any suitable character but I prefer to employ a small mesh wire fabric, as shown in the drawing. The screen is formed in sections and each section comprises a strip of foraminous material, as

shown at 7, the lateral portions of which are bent downwardly to provide vertical portions 8 and 9 to extend into the upper portion of the eaves trough and to rest upon suitable supports therein. With the type of eaves trough here shown I utilize fastening devices for the trough as the support for the screen and the lower edges of the downwardly turned, or vertical, portions 8 and 9 of the screen rest upon these fastening devices. The screen is sprung into position in the upper portion of the trough with its inner portion beneath the overhanging edges of the shingles and will be retained in position therein without fastening devices. If desired, the vertical portions 8 and 9 of the screen may be arranged at such angles to the body or transverse portion of the screen that when inserted between the front and rear walls of the eaves trough they will be placed under compression so that the natural resiliency of the material will cause them to firmly grip the respective walls of the trough, thus firmly retaining them in position. While the screen will be firmly retained in position without additional retaining means I prefer to provide the forward vertical portion 8 thereof, at its lower edge, with an out-turned portion or flange 10 which, when the screen is placed in position, will extend between the fastening devices and the flange 3 at the upper edge of the front wall of the trough, thus positively preventing the vertical displacement of the trough. The resiliency of the material permits the screen to be readily sprung into position and when released the flange 6 will engage beneath the flange 3 of the trough.

I also prefer to so support the screen that it will extend downwardly and forwardly across the open upper side of the eaves trough, in an inclined position. This I accomplish by making the downwardly turned or vertical portion 9 at the inner edge of the screen of greater width than the corresponding portion 8 at the outer edge of the screen, thus when the two vertical portions rest on the fastening devices the transverse portion of the screen will be in an inclined or sloping position and any leaves or other material which may fall thereon will tend to slide off the screen or be washed off the same by the water which flows off of the shingles onto the screen. In this manner the leaves are prevented from accumulating on the screen and inter-

fering with the passage of the water from the roof to the eaves trough.

The several sections of the screen may be connected one to the other, if desired, and this may be readily accomplished by extending a part of the longitudinal wires of one section beyond the end of the screen proper and turning the same down, as shown at 11, to form hooks which may be engaged through the end meshes of the adjacent section, thus holding the two sections against longitudinal displacement with relation one to the other.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:—

1. A screen for an eaves trough, comprising a section of foraminous material having its lateral portions turned downwardly and arranged to be inserted in said eaves trough, one of said down turned portions having an outwardly turned flange to extend beneath a part extending inwardly from the upper edge of the adjacent wall of said eaves trough.

2. A screen for an eaves trough, comprising a section of foraminous material having its lateral portions turned downwardly to engage supports within said eaves trough, said down turned portions being of such relative width that the transverse portion of said screen will slope downwardly toward the outer wall of said eaves trough.

3. The combination with an eaves trough, comprising front and rear walls, and fasten-

ing devices extending through said walls and spaced from the upper edges thereof, of a section of foraminous material having its lateral portions bent downwardly and arranged to enter the upper portion of said eaves trough and to engage said fastening devices. 45

4. The combination with an eaves trough, comprising front and rear walls, and fastening devices extending through said walls and spaced from the upper edges thereof, of a section of foraminous material having its lateral portions bent downwardly and arranged to enter the upper portion of said eaves trough and to engage said fastening devices, the inner downturned portion of said screen being of greater width than the outer downturned portion thereof to cause the body of said screen to slope toward the 55 front wall of said trough.

5. The combination with an eaves trough, comprising front and rear walls, the front wall having its upper edge turned inwardly to form a flange, and fastening devices extending through said front and rear walls to secure said trough to a supporting structure, said fastening devices being spaced from the upper edges of said walls, of a section of foraminous material having its lateral portions turned downwardly and arranged to enter the upper side of said eaves trough and to rest upon said fastening devices, that downturned portion adjacent to the front wall of said trough having at its lower edge 75 an outwardly extending portion to engage beneath the flange on said front wall of said eaves trough.

In testimony whereof, I affix my signature hereto.

JAMES C. ANDREWS.
